A. I. RISER

CLUTCH

Original Filed Oct. 15, 1923

Inventor:
Arthur I. Risser
By Cheverton & Atlys

UNITED STATES PATENT OFFICE.

ARTHUR I. RISSE, OF CHICAGO, ILLINOIS, ASSIGNOR TO U. S. BOTTLES' MACHINERY CO., OF CHICAGO, ILLINOIS, A CORPORATION OF ILLINOIS.

CLUTCH.

Original application filed October 15, 1923, Serial No. 668,457. Divided and this application filed April 7, 1924. Serial No. 704,558.

To all whom it may concern:

Be it known that I, ARTHUR I. RISSE, a citizen of the United States, residing at Chicago, in the county of Cook and State 5 of Illinois, have invented a certain new and useful Improvement in Clutches, of which the following is a specification.

This application is a division of my earlier 10 application for bottle filling machine, Serial Number 668,457, filed October 15, 1923.

This invention relates to clutches but more particularly to clutches having special value in machines of the above mentioned class in which a reciprocating member, specifically a bar, carries a siphon which has to be inserted in and withdrawn from the neck of a bottle placed on a table adjacent to the end of the bar, it being necessary that the siphon be accurately positioned and carried in order to prevent its striking the sides of the neck of the bottle and breaking it instead of entering the bottle as its should for proper functioning of the machine.

The object of the invention is to provide 25 a clutch which is especially applicable to the foregoing use; which can be very easily and cheaply made; which is very accurate and efficient in operation and is not readily liable to get out of order.

The invention consists in means attaining 30 the foregoing and other objects which will be hereafter more fully set forth in the specification and claims.

Referring to the drawings, Figure 1 is a 35 fragmentary view of part of a bottle filling machine in which the clutch of this invention, shown partially in section, is in use.

Figure 2 is a side view, taken from the 40 right of the clutch mechanism appearing in Figure 1.

Figure 3 shows the parts of the clutch mechanism in disassembled condition.

In equipping the, for the purpose of this 45 invention, conventional bottle filling machine with the mechanism of this invention, the lower end of a vertical, reciprocal bar 10 is provided with a suitable coupling or clutch 12 carrying a siphon 14 having a relatively short arm 16 adapted to enter an adjacent bottle 18 to be filled resting on table 20 in approximately the position shown in Figure 1 and a comparatively longer arm

22 entering the liquid tank 24 to a point materially below the level of the liquid 26 which is to be transferred from the tank 55 into the bottle.

In the particular embodiment of the invention here illustrated, the coupling 12 is detachably secured to the adjacent bar 10 by means of a suitable bolt or set screw 60 28 and is recessed at its lower end to receive a handle or stem 30 rigid with the siphon tube 14, said stem being detachably rigidly secured in place by set screw 32 in the outer wall of the clutch having its 65 pointed end entering a V-shaped notch 34 formed in the stem. The stem 30 carries one or more projecting lugs 36, each entering a suitable notch 38 provided for it in the lower end of the clutch, the same adapted to prevent rotation of the siphon on a vertical axis through the bar 10. For the same reason, the lower end of bar 10 rests in notches 40 cut in opposite sides of clutch coupling 12. By thus holding the siphon 70 against rotation and by rigidly securing it through the action of set screw 32, engaging notch 34, each siphon is rigidly, positively positioned for operative work in relation to filling bottle 18 as fully set forth in said 75 original application.

Having thus described my invention, what I claim as new and desire to secure by Letters Patent is:

1. A clutch device for detachably connecting a siphon of a bottle filling machine to a siphon support, comprising a member secured to the support, a cylindrical opening in said member adapted to receive a cylindrical stem on the siphon to be connected with the support, means to secure the siphon stem against longitudinal movement within the opening in said member, and means to prevent rotation of the siphon stem within the opening in said member 95 consisting of a lug on the stem adapted to enter a notch in the member, said notch and lug cooperating to limit inward movement of the stem within the member.

2. A clutch device for detachably connecting a siphon of a bottle filling machine to a siphon support, comprising a tubular member one end of which is detachably connected to the support and the other end of

which is adapted to receive a stem on the siphon, a screw passing transversely through a wall of the tubular member into an annular recess in the stem to secure the stem against longitudinal movement within the tubular member, and a lug on the stem entering a notch formed in and opening

through one end of the tubular member to prevent rotation and limit inward movement of the stem within the member.

In witness whereof, I have hereunto subscribed my name.

ARTHUR I. RISSE.
